UNITED STATES PATENT OFFICE.

WILLIAM CRAIG, OF JAMESTOWN, NEW YORK.

REVOLVING BOOT-HEEL.

SPECIFICATION forming part of Letters Patent No. 253,348, dated February 7, 1882.

Application filed July 26, 1881. (No model.)

To all whom it may concern:

Be it known that I, WILLIAM CRAIG, of Jamestown, in the county of Chautauqua and State of New York, have invented certain new and useful Improvements in Revolving Boot-Heels; and I do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal vertical section of a boot provided with my revolving heel. Fig. 15 2 is a vertical cross-section at right angles to Fig. 1. Fig. 3 is a bottom view of the heel with the bottom lifts removed, and Fig. 4 is a perspective view of the heel pivot or spindle detached.

20 Similar letters of reference indicate corresponding parts in all the figures.

My invention contemplates an improved construction of revolving heels for boots and shoes, as hereinafter more fully set forth, and particularly pointed out in the claim.

25 In the annexed drawings, A represents the heel portion of a gaiter, boot, or shoe, as the case may be, provided with my improved heel. The latter is made in two sections—viz., an 30 upper section or top part, B, which is of circular shape, and nailed to the insole in the usual manner, and a circular revolving disk or section, C, built up of a suitable number of lifts or taps to make it of the requisite height.

35 The pivot or spindle upon which the revolving heel-disk C is secured is composed of four parts, cast in one piece, of iron, brass, or other suitable metal—viz., a cylindrical middle part or shank, D, a circular plate or disk, E, a centrally-projecting lug, F, and a cross-head, G, at the lower end of the shank, which is made with two notches, g g, one at each end. The plate E is held in a chamber, a, between two of the lifts of the rigid top part, B, of the 40 heel, with its lug or central point, F, projecting up into a cavity, f, in the center of the chamber a, so that the plate is enabled to turn within its recess a around point F as its center.

The lifts which form the rotating part C are 45 built up around the spindle-shank D, each hav-

ing a slot, d, sufficiently large to admit of the insertion of the cross-head G, after which the lifts are turned to one side, so as to interlock with the cross-head, as shown in Fig. 3, after which they are secured by nails h, driven into the part 55 C through the end notches, g g, in cross-head G. The heel is then finished by placing the bottom lifts, i, over the cross-head and heads of the nails h, said lifts being fastened by nails or screws k. The bottom part, i, is recessed 60 to receive the cross-head G, so that the whole part C will present a neat and finished appearance.

The circular plate E of the central spindle should be held or clamped with sufficient firmness between the lifts of the top part, B, between which it is inserted, to prevent it from turning too easily, so that the rotary part C, which is rigidly connected to the spindle, will not be likely to turn accidentally or of its own account. As the heel becomes worn on one side it may be turned with the hands so as to bring a fresh part to bear, and in this manner the heel will be worn evenly all around, all that is necessary to keep it in perfect repair 75 being an occasional renewal of the bottom lift, i.

Having thus described my invention, I do not claim broadly a revolving heel, as I am well aware such have been made before; but 80

What I claim as my improvement, and desire to secure by Letters Patent of the United States, is—

The combination, in a revolving heel for boots or shoes, of the stationary part B, having the central recess, f, and chamber a, spindle D, having the top plate, E, provided with the central lug, F, and notched bottom cross-head G, and revolving part C, attached permanently to the spindle D, substantially as and 85 for the purpose herein shown and described.

In testimony that I claim the foregoing as my own I have hereunto affixed my signature in presence of two witnesses.

WILLIAM CRAIG.
